SIGNPOST PAPERWEIGHT

Mae I. Klein and Dorothy B. Nystrom,
Lancaster, Pa.

Application February 2, 1951, Serial No. 14,086

Term of patent 3½ years

(Cl. D74—12)

To all whom it may concern:

Be it known that we, Mae I. Klein and Dorothy B. Nystrom, citizens of the United States, residing at Lancaster, in the county of Lancaster and State of Pennsylvania, have invented a new, original, and ornamental Design for Signpost Paperweight, of which the following is a specification, reference being had to the accompanying drawing, forming a part thereof.

Figure 1 is a perspective view of a signpost paperweight embodying the invention;

Fig. 2 is a perspective view of the signpost paperweight shown in Fig. 1 with the paperweight turned ninety degrees in a clockwise direction;

Fig. 3 is a side elevation of the signpost paperweight shown in Fig. 1; and

Fig. 4 is a top plan view of the signpost paperweight shown in Fig. 1.

The base is lined to indicate the colors green, red, and yellow. The bottom of the base is plain and flat.

We claim:

The ornamental design for a signpost paperweight, as shown and described.

MAE I. KLEIN.
DOROTHY B. NYSTROM.
